8 Claims. (Cl. 340—166)

This invention relates to magnetic core matrices and more particularly to an improved means for selecting a particular core in a matrix.

In the prior art, bidirectional or two coordinate matrices are commonly employed; such matrices generally comprise binary elements having two stable states of energization such as magnetic cores or ferroelectric capacitors. The binary elements may be considered to be arranged in rows and columns and a plurality of current carrying or drive lines pass through the rows and columns of elements, that is, the drive lines in the rows cross the drive lines in the columns and a binary element is located at each intersection. To energize any one of the elements in a matrix, it is necessary to coincidentally energize a drive line in one of the rows and a drive line in one of the columns. The magnitude of the current at the intersection of the drive lines which are energized is sufficient to drive the element located at said intersection.

In the prior art type of matrices in which coincident currents are utilized to cause the binary elements to shift from one to the other of their stable states, it is necessary that the elements have rectilinear hysteresis groups.

Accordingly, it is a principal object of this invention to provide an improved means for selecting a particular binary element in a matrix.

It is another object of this invention to provide a means of selecting a binary element other than by energizing the element by coincidence or anticoincidence.

It is another object of this invention to provide a magnetic core matrix in which the cores of the matrix need not necessarily have rectilinear hysteresis loops.

It is yet another object of this invention to provide a matrix in which a minimum number of current driver means are employed.

According to a preferred embodiment of the present invention, a matrix comprising a plurality of magnetic cores arranged in a plurality of groups are employed; for simplicity in description, the cores are considered to form rows and columns. Each of the cores has wound thereon a primary or input winding, a secondary winding or output winding and a control winding. The primary winding on each of the cores in a row is connected in series to a current driver. The control windings of cores in a column are connected in parallel to a gating means which selectively completes an electrical circuit for, or open circuits the associated control windings. The gating means are normally closed, therefore, maximum current in the primary winding is coupled to the associated control windings and a minimum current is coupled to the associated secondary winding.

To select a core, an address decoder activates a particular current driver for providing current to one of the rows of cores and the address decoder opens a gating means for a column of cores. When the gating means are opened, the control windings connected thereto are open circuited and a minimum current from the primary winding is coupled to the associated control winding and a maximum current is coupled to the secondary winding. Therefore, only in the core positioned at the coordinate of the selected row and column is a maximum current coupled from the primary to the secondary winding.

The foregoing and other objects, features and advantages of the invention will be apparent from the following more particular description of preferred embodiments

2

of the invention, as illustrated in the accompanying drawings.

In the drawings:

FIG. 1 shows a matrix in accordance with the invention;

FIG. 1a shows the termination of the secondary windings of FIG. 1;

FIG. 1b shows a modification of the termination of FIG. 1a.

FIG. 1 shows a matrix 11 according to the invention. A relatively simple form of a single plane matrix is shown for purposes of facilitating the explanation of the operation of the invention. It will, however, be appreciated that the size of the matrix and the number of cores used are essentially unlimited. Matrix 11 comprises sixteen magnetic cores arranged in a two coordinate system or, more specifically, in four rows and four columns. The rows of cores are designated alphabetically as rows A, B, C and D; the columns of cores are designated as columns 1, 2, 3, 4; each core may be designated by its coordinate, for example, core 1A is positioned at the intersection of column 1 and row A.

Each of the cores in matrix 11 includes a primary winding NP, secondary winding NS and a control winding NC for purposes to be explained more fully hereinbelow. In FIG. 1a, only the windings on core 1A are lettered since the corresponding designation of the windings on the other cores of the matrix are readily apparent. A group of current carrying or drive lines 13, 14, 15 and 16 are each serially connected to the primary winding NP of the cores in rows A, B, C and D respectively for providing an input to the cores. Current amplifiers or drivers 23, 24, 25 and 26, of any suitable known type, and capable of providing a fairly constant current, are connected to drive lines 13, 14, 15 and 16, respectively.

The control windings NC of the cores in the columns 1, 2, 3 and 4 are connected to common lines 31, 32, 33 and 34, respectively. The control windings of cores in a column are thus connected in parallel with respect to one another. One terminal of each of lines 31, 32, 33 and 34 is connected to ground reference and the other terminals of lines 31, 32, 33 and 34 are connected to gating stages 41, 42, 43 and 44, respectively.

Each of the electrical paths for the control windings is similar. For example, with reference to line 31 and core 1A, the electrical path may be traced from ground reference through line 31, the control winding NC of core 1A, a diode 45, back to line 31 and gate 41 to ground, as will be explained hereinbelow.

Gating stages 41-44 are each connected to an address decoder 69 of any suitable known type which is adapted to change the machine address forms to a matrix format in order to select one out of n gates in one dimension for one character and one out of n drivers in a second dimension for a second character.

Each of gating stages or gates 41-44 comprises a pair of transistors 51 and 55. Each of the gates are similar and operate in the same manner so that the description and showing of gate 41 applies equally well to gates 42, 43 and 44. Transistor 51 is an NPN type transistor including an emitter 52, a base 53 and a collector 54. The emitter 52 is connected to ground reference, base 53 is connected through a resistor 59 to a negative potential $-V_3$, and collector 54 is connected through a resistor 61 to a first positive potential V_1 and through a reverse biased diode 63 to a second positive potential V_2 ; that is, the anode of diode 63 is connected to collector 54, and the cathode of diode 63 is connected to V_2 . An input signal is coupled from address decoder 69 through a resistor 60 to the base 53 of transistor 51.

Transistor 55 is a PNP type transistor including an emitter 56, a base 57 and a collector 58. The emitter

56 is connected to the common line (for gate 41, emitter 56 is connected to line 31) to which the control windings of a column of cores are connected in parallel. The base 57 is connected to the collector 54 of transistor 51, and through resistor 61 to potential V1 and through diode 63 to potential V2. The collector 58 is connected to a negative biasing potential VP.

Transistor 51 is biased to normally be conducting. With transistor 51 conducting, its collector 54 is essentially connected to ground potential. A ground or zero potential is thus coupled to the base 57 of transistor 55 causing transistor 55 to be conductive; emitter follower action lowers the potential of the emitter 56 of transistor 55 to essentially ground potential. With transistor 55 conducting, an electrical circuit is completed through the control winding of each of the cores in the column of cores associated therewith. For example, for the control windings of the cores in column 1, a circuit is traceable from ground, parallel or common line 31, the control windings of the cores in column 1, the respective diodes, the emitter 56 to base 57 path of transistor 55 and through the collector 54 to emitter 52 path of transistor 51 to ground reference. When a complete electrical circuit for a control winding is formed, the control winding will, in essence, be short circuited and there will be a minimum transfer of energy from the associated primary winding to the associated secondary winding, as will be explained hereinbelow.

To select a core, address decoder 69 activates the current driver for the row of cores in which the core to be selected is positioned and provides a negative potential to open the gate controlling the column of cores in which the core to be selected is positioned. For purposes of description, assume core 1A is to be selected. Address decoder 69 activates current driver 23 and opens gate 41. The operation of the circuitry is as follows: A negative potential coupled through resistor 60 to the base 53 of transistor 51 biases transistor 51 to become nonconductive or cut off. When transistor 51 cuts off, diode 63 is forward biased and clamps the potential at the base 57 of transistor 55 at V2 which biases transistor 55 to cut off. When transistor 55 cuts off, the electrical circuit for the control windings of the associated column of cores is open circuited until a potential equal to V2 is established across the control winding at which point transistor 55 turns on, thus clamping the control potential at this level; that is, any higher voltage energy developed by the primary winding is dissipated in the control winding. This, in turn, establishes a clamped voltage on the secondary windings NS of the associated column of cores and provides a positive current control. Core 1A, positioned in the row for which current driver 23 has been activated and also positioned in the column for which gate 41 has been opened, will provide a predetermined transfer of energy from primary winding NP to the secondary windings NS, as will be explained hereinbelow.

Referring now also to FIGS. 1a and 1b, the secondary windings NS of each of the cores in matrix 11 are connected in series with the input windings of groups of cores in a memory array.

In a first embodiment of the invention, as seen in FIG. 1a, each of the secondary windings NS of the cores in matrix 11 are connected in series with a respective group of cores in the memory array and with a diode circuit for purposes of reducing any undesired current flow in the secondary windings NS of the unselected cores when the control winding of the selected core is in its short circuit condition, for purposes to be described below. Only seven of the cores of matrix 11 are shown since this is believed sufficient to an understanding the invention; it will, of course, be appreciated that the other cores of matrix 11 are connected similarly to core groups in the memory array. One terminal of each of the secondary windings NS is connected to a common line 68, and the other terminal of the secondary winding NS is connected in series through the windings of the cores in respective

5 groups of the memory array. For example, one terminal of secondary winding NS of core 1A is connected in series with core group 104 in the memory array. The lower terminal, as oriented in FIG. 1a, of each of the memory array groups divides into two paths. For example, for group 104, the first path is traceable through a diode 88 and lead 100 to the right-hand terminal, as oriented in FIG. 1a, of a resistor 99; the anode of diode 88 is connected to the junction of the two paths and its cathode connected to lead 100 and resistor 99. The second path is traceable through a diode 87 and lead 110 to the left-hand terminal or resistor 99; the cathode of diode 87 is connected to the junction of the two paths and its anode is connected to lead 110 and resistor 99. Diodes 82, 84, 86, 88, 90, 92 and 94 associated with memory core groups 101, 102, 103, 104, 105, 106 and 107, respectively, are connected in common to lead 100. Likewise, diodes 81, 83, 85, 87, 89, 91 and 93, associated with memory core groups 101, 102, 103, 104, 105, 106 and 107, respectively, are connected in common to lead 110.

10 In a second embodiment of the invention, as seen in FIG. 1b, each of the secondary windings NS is connected in series with a respective group of cores and a terminating resistor to ground reference. The secondary winding NS of core 1A, for example, is connected through lead 74 in series with a group of cores 104 in the memory array, and a terminating resistor 114 to ground reference. Current flowing through each of the secondary windings NS thus flows through the respective group of cores 101, 102, 103, 104, 105, 106 or 107, and is dissipated in the respective terminating resistor 111, 112, 113, 114, 115, 15 116 or 117.

20 In a second embodiment of the invention, as seen in FIG. 1b, each of the secondary windings NS is connected in series with a respective group of cores and a terminating resistor to ground reference. The secondary winding NS of core 1A, for example, is connected through lead 74 in series with a group of cores 104 in the memory array, and a terminating resistor 114 to ground reference. Current flowing through each of the secondary windings NS thus flows through the respective group of cores 101, 102, 103, 104, 105, 106 or 107, and is dissipated in the respective terminating resistor 111, 112, 113, 114, 115, 25 116 or 117.

25 Ideally, when current is flowing through the control winding NC of the associated core, the winding NC will be short circuited and no voltage will be induced thereacross. All the current will thus flow through the control winding and no current will flow in the associated secondary or output winding. Further, the impedance reflected back from the control winding NC to the associated primary winding NP will be zero; thus, no voltage will be reflected back by the control winding NC to the primary winding or to the secondary winding.

30 Ideally, when current is flowing through the control winding NC of the associated core, the winding NC will be short circuited and no voltage will be induced thereacross. All the current will thus flow through the control winding and no current will flow in the associated secondary or output winding. Further, the impedance reflected back from the control winding NC to the associated primary winding NP will be zero; thus, no voltage will be reflected back by the control winding NC to the primary winding or to the secondary winding.

35 It has, however, been found that even during the period when the associated gates are closed and maximum current is flowing in the control windings, that is, the winding is in essence, short circuited, the control windings together with the associated diode and the transistor of the associated gate may still reflect a significant impedance into the primary winding. For example, in core 1A, the control winding NC, diode 45 and transistors 51 and 55 in gate 41 may reflect a significant impedance to the primary winding. The impedance of secondary windings NS, the impedance of the windings on the cores of the respective memory array, and the impedance of any resistors in the respective lines are also reflected to the primary winding. This causes the current flowing in the primary windings to divide between the associated control winding and the secondary winding according to the ratio of the reflected impedance. The ratio of the turns of the control winding and of the secondary winding are selected to provide a low secondary voltage.

40 The termination or circuit of FIG. 1b is satisfactory, for example, if, during the short circuited condition of the respective control winding, any current induced in the secondary windings NS which may flow through the respective drive line for a group of cores in the memory array is not of sufficient magnitude to adversely affect the operation of the cores in the memory array. The foregoing condition may exist in some two dimensional arrays. In those two dimensional arrays in which the current flowing in those drive lines not associated with the selected core is of sufficient magnitude to adversely affect the operation of the memory cores; and, in the three dimensional arrays, the circuitry of FIG. 1a is of specific importance. It has been found that in three

dimensional arrays, the currents in the various drive lines normally tend to add to cause improper operation of the cores in the memory array.

The operation of the embodiment of FIG. 1a will now be described. As indicated above for simplicity in explanation, only a few of the cores of matrix 11 are shown in FIG. 1a; however, the operation as described applies to the overall matrix. Assume that core 1A of matrix 11 is selected and that a voltage VX is developed across the secondary winding NS; lead 74 connected to winding NS of core 1A will be at potential VX. Since the impedance of the windings of the memory array is relatively low, the junction of diodes 87 and 88 is also essentially at potential VX. Diode 88 will be forward biased and since it has a relatively low forward impedance, lead 100 will also be essentially at potential VX.

As described above, to select core 1A, current driver 23 drives a current through line 13 and thus through the primary windings NP of all the cores in row A. Each primary winding NP will also transfer an amount of energy to the associated secondary winding NS of all the other or unselected cores in row A. A voltage, designated as VY, which is of lesser magnitude than voltage VX will thus be developed across the secondary winding NS of the unselected cores in row A, namely, in cores 2A, 3A and 4A. Due to the relatively low impedance of the windings of the memory array groups 105, 106 and 107, the voltage VY appearing on leads 75, 76 and 77 will be impressed at the junction of diodes 89-90, 91-92 and 93-94, respectively. However, since diodes 90, 92 and 94 are connected in common to line 100, as is diode 88 and since voltage VX is of a larger magnitude, that is, more positive, than voltage VY, diodes 90, 92 and 94 will be reverse biased.

The current drivers associated with rows B, C, and D are not activated, consequently, no current will be induced in the respective secondary windings NS of the cores in these rows; therefore, the potential on the secondary windings of the cores in these rows will be essentially zero volts, designated as VO. Due to the relatively low impedance of the windings in core groups 101, 102, and 103, the voltage VO appearing on leads 71, 72 and 73 will be impressed at the junction of diodes 81-82, 83-84 and 85-86. Diodes 82, 84 and 86, which have their cathodes connected to lead 100 and thus to potential VX will be reverse biased; however, diodes 81, 83 and 85 which have their anodes connected to lead 110 will be forward biased. Current will flow from the more positive potential VX to potential VO through diode 88, lead 100 and resistor 99 to lead 110; the current will then divide approximately evenly and flow through diodes 81, 83 and 85, the respective memory array groups 101, 102 and 103, through leads 71, 72 and 73 and the respective secondary windings of the cores in rows B, C and D to common line 68.

The voltage drop developed across resistor 99 causes the potential on lead 110 to be less than VY so that diodes 89, 91 and 93 are reverse biased and no current flows through the respective memory arrays 105, 106 and 107. Thus, current is prevented from flowing in the secondary windings NS of the cores, other than the selected core, in a row which is energized by a current driver. The current flowing through each of the secondary windings in rows B, C and D is of a relatively very low magnitude and does not affect the operation of the cores in these rows.

The operation will, of course, be similar to the above when any other core in the matrix 11 is selected.

If the primary winding NP induces a negative potential in the lead connecting the secondary windings NS to the respective memory array groups, the junction of the respective diodes will be at a negative potential and current would tend to flow in the opposite direction of

that stated above. However, the principle of operation of the circuit is the same.

By insuring that the current flowing in the primary winding NP of the selected core is more than sufficient to supply the desired current in the associated secondary winding NS, some current will always flow through the associated control winding NC. Since the wave shape of the current flowing in the control winding NC is of no consequence, the material from which the cores are made can have a non-rectangular hysteresis loop. Any drop which might occur in the current flowing in the secondary winding NS can be made to occur almost entirely in the control winding NC while the current is flowing in the secondary winding is clamped to essentially a square wave output.

If close regulation is desired during the reset cycle, that is, during the period when the cores shift their magnetic state during the read operation; or, if sufficient flux is switched in the "unselected" cores during the set cycle (during the writing operation) to provide an unacceptable amount of output energy upon resetting, a second group of gates can be connected to each column of cores. This second group of gates is similar to the gates 41-44 shown in FIG. 1a, and each gate of the second group is connected to a respective control winding in parallel to an associated one of gates 41-44. For the second group of gates, the polarity of operation would vary between a minus voltage and ground reference; therefore, the transistor corresponding to transistor 55 would be an NPN type transistor with its emitter connected through a common line and a diode to the respective control winding; the diode would have its cathode connected to the control winding and its anode connected to the respective transistor. The operation of the second group of gates during the reset operation would be similar to that of gates 41-44 during the set operation; as noted, the variation in voltage to operate the second group of gates would be opposite of that for gates 41-44; that is, from a negative potential to ground rather than from a positive potential to ground.

While the invention has been particularly shown and described with reference to preferred embodiments thereof, it will be understood by those skilled in the art that the foregoing and other changes in form and details may be made therein without departing from the spirit and scope of the invention.

What is claimed is:

1. A matrix comprising, in combination, a plurality of cores; a primary, a control and a secondary or output winding on each of said cores; means selectively connected to said primary windings for energizing said cores; a plurality of gating means each having first and second conducting conditions; respective unilateral conducting means connecting one terminal of said control windings to an associated gating means, the other terminal of said control windings being connected to a reference potential; each of said gating means being respectively connected to the control windings of selected cores; means for selectively activating the gating means from the first to the second conducting conditions for respectively completing and opening an electrical circuit for the associated control windings; said gating means in a first condition connecting a voltage at said reference potential to said one terminal of the associated control windings for providing an effective zero bias across said unilateral conducting means; the associated control winding thus being essentially short circuited to provide a counter energization to said primary winding energization to thereby obtain an output signal on the associated output windings of a low magnitude; and said gating means in second condition connecting a voltage of a second potential to said unilateral conducting means for reverse biasing said unilateral conducting means; primary winding energization when above a selected magnitude causing a voltage to be developed across the associated control winding for forward biasing

the associated unilateral conducting means to thereby permit current flow therethrough and hence provide a counter energization for controllably clamping said output signal at a second selected magnitude.

2. A matrix in accordance with claim 1 in which said unilateral conducting means are diodes.

3. A matrix in accordance with claim 1 in which said gating means are connected in parallel to a column of cores, and in which primary energizing means are connected to the primary windings of a row of cores whereby a core is selected to provide an output from its secondary winding by energizing the primary windings of an associated column of cores and activating an associated gating means to its second conducting condition.

4. A matrix in accordance with claim 1 wherein each gating means comprises a pair of transistors biased to conduction in a first conducting condition and biased to cut-off in a second conducting condition.

5. A matrix in accordance with claim 1 wherein said gating means comprises a pair of transistors each having base, emitter and collector electrodes; the base of the first of said transistors being connected to the collector of the second of said transistors; sources of operating potentials for said transistors; means for applying a first potential to the base of said first transistor to cut-off said first transistor; said first transistor being biased to conduct when the voltage developed across the associated control winding overcomes the biasing effect of said first potential and thereby clamps the voltage appearing across said secondary winding to said first potential; the electrical circuit for the associated control windings being traceable through the emitter-to-base path of the first of said transistors and the collector-to-emitter path of the second of said transistors.

6. A matrix in accordance with claim 1 wherein each of said secondary windings has one end connected to a reference line and its other end connected in series with a terminal of the windings of a memory array arranged in groups; a diode connected to the other terminal of the windings of each memory array group, a resistor connecting each of said diodes to a common line, current flowing through the secondary winding of a selected core and said resistor causing the diodes connected to the secondary windings of the cores in an energized group to be reverse biased to thereby prevent current flow through the unselected cores of an energized group and the respective memory array.

7. A matrix in accordance with claim 1 wherein each of said secondary windings has one end connected to a reference line and its other end connected in series with a terminal of the windings of a memory array; a pair of diodes connected to form a parallel junction at the other terminal of the windings of each memory array group; one diode of each pair having its anode connected to said

junction and its cathode connected to a first common line; the other diode of each pair having its cathode connected to said junction and its anode connected to a second common line; a resistor connecting said first and second common lines, the voltage developed across the secondary winding of the selected core causing one of the diodes of each pair connected to the unselected cores to be reverse biased; current flowing through the secondary winding of a selected core and said resistor reverse biasing the other diode in each pair connected to the secondary windings of the cores in an energized group to thereby prevent current flow through the unselected cores of an energized group and the respective memory array; current flow through said resistor forward biasing the diodes connected to the cores in the unenergized groups whereby current induced in the secondary winding of the selected core divides and flows through said forward biased diodes, the associated memory array windings and the associated secondary windings to said reference line.

8. A matrix in accordance with claim 1 wherein said gating means comprises a first PNP type transistor and a second NPN type transistor, each having base, emitter and collector electrodes; biasing means for providing operating potentials to said transistors; said first transistor having its emitter connected in parallel to the control windings of a core in each of said groups, its collector connected to a first potential, and its base connected to the collector of said second transistor to receive the output signal therefrom; impedance means connecting the base of said first transistor to said biasing means for providing a second potential to said base, the emitter of said second transistor being connected to ground reference; said biasing means normally causing both said transistors to be conductive; means for connecting an input signal to the base of said second transistor to render both said transistors nonconductive and thereby open said gating means; said transistors remaining nonconductive until the voltage developed across the associated control winding is of sufficient magnitude to raise the potential of the emitter of said first transistor to said second potential level whereby said transistors conduct and a circuit is completed for the associated control windings whereby any energy in excess of said second potential level is dissipated in said completed circuit and whereby the voltage appearing across said secondary winding is clamped to a level determined by said second potential.
